[57] CLAIM

The ornamental design for a turbine engine, as shown and described.

DESCRIPTION

FIG. 1 is a perspective view of a turbine engine showing my new design;

FIG. 2 is a front elevational view thereof;

FIG. 3 is a rear elevational view thereof;

FIG. 4 is a side elevational view thereof;

FIG. 5 is a side elevational view of the side opposite that shown my new design;

FIG. 6 is a top plan view thereof; and,

FIG. 7 is a bottom plan view.

FIG. 1

FIG. 2

FIG. 3

FIG. 4

FIG. 5

FIG. 6

FIG. 7
